(57) **CLAIM**

The ornamental design for a desk, as shown and described.

DESCRIPTION

1. Desk

1.1 is a right side profile view of the desk showing my new design, trays are in a horizontal and flat position; and 1.2 is a rear and left side perspective view of the desk showing the rear tray in a lowered position and the front tray in a raised position.

Protection is not sought for those portions of the desk shown in broken lines, and such portions form no part of the claimed design.
